(57) **CLAIM**

The ornamental design for a headlamp, as shown and described.

DESCRIPTION

FIG. 1 is a perspective view of a headlamp showing my new design thereof;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view;

FIG. 8 is another perspective view thereof; and,

FIG. 9 is the perspective view thereof, shown in use;

The broken lines shown in FIG. 4 and FIG. 9 are for environmental purposes. All other broken lines shown portions of the article not claimed. The broken lines form no part of the claimed design.

The stipple shading and the straight line shading show a contrast in appearance.
